WATER DRINKING FOUNTAIN

Halsey W. Taylor, 205 Golf Drive NE., Warren, Ohio

Filed Nov. 29, 1960, Ser. No. 63,011

Term of patent 14 years

(Cl. D67—4)

The dominant features of my invention reside in the portions shown in full lines.

I claim:

The ornamental design for a water drinking fountain, substantially as shown and described.
